US0D1097616S

(12) United States Design Patent (10) Patent No.: US D1,097,616 S
(45) Date of Patent:  Oct. 14, 2025

(54) SOFA

(71) Applicant: Molteni & C. S.p.A., Giussano (IT)

(72) Inventors: Vincent Van Duysen, Antwerp (BE);
Yabu Pushelberg, Toronto (CA)

(73) Assignee: Molteni & C. S.p.A., Giussano (IT)

() Term: 15 Years

(21) Appl. No.: 35/521,473

(22) Filed: May 28, 2024

(80) Hague Agreement Data

Int. Filing Date: May 28, 2024

Int. Reg. No.: DM/237945

Int. Reg. Date: May 28, 2024

Int. Reg. Pub. Date: Jun. 28, 2024

(30) Foreign Application Priority Data

Nov. 28, 2023 (IT) 402023000003453

(51) LOC (15) Cl. 06-01

(52) U.S. Cl.

USPC D6/369

(58) Field of Classification Search

USPC D6/334, 335, 361, 369, 377, 378, 381,
D6/382, 390, 393

CPC A47C 5/00; A47C 5/02; A47C 7/00; A47C
7/40; A47C 7/50; A47C 17/00; A47C
17/02
